(57) **CLAIM**

The ornamental design for a headset microphone with transparent portion, as shown and described.

DESCRIPTION

FIG. 1 is a front perspective view of a headset microphone with transparent portion showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in FIGS. 1-8 show portions of the headset microphone with transparent portion that form no part of the claimed design. At the tip end of the microphone, broken lines illustrate disclaimed internal elements, and are shown to illustrate the transparency.
